Burton H. Locke, Framingham, Mass.

Application March 14, 1950, Serial No. 149,478

2 Claims. (Cl. 132—1)

This invention relates to improvements in trays for holding any type of closed hair pins which will be referred to hereinafter as bobby pins.

The object of the invention is to provide a tray of a form that will permit such pins to be opened on the top edge thereof by pulling the prongs of the pins apart downwardly from the said edge with one hand, after one of the prongs has been positioned on the said edge, while the other hand is being utilized to hold the lock 10 of hair to be pinned. 5

Another object is to combine a pin opening means at the top edge of a tray where it will always be at hand and be positioned most conveniently for use as the pins are removed from the tray for application to the hair.

The objects of the invention are accomplished by the provision of a suitable edge at the top of the sides of the tray for easy wedging between the prongs of bobby pins to start the opening thereof as the pin is pushed thereagainst as it is handled in one hand from the tray to the hair which is being held in the other hand, and to afford a tray that will not tip or move about as the pressure of opening the pin is applied to the said upper edge of the tray.

The procedure of opening bobby pins in the manner to be set forth herein will eliminate the present usual methods of opening the pins on one's teeth or finger nails or on parts of furniture which will thus avoid the possibilities of damage to the teeth or nails or to furniture, respectively.

In order to afford a tray that will permit quick and proper placement of the pin thereon for spreading of the prongs, I conceive to provide a relative sharp wedge-shaped corner on the top of the rim by shaping the said corner in the form of an acute angle. Such a corner facilitates the initial wedging open of the prongs of the pin as the pin is pushed thereagainst which assures the placing of one of the prongs, preferably the longer prong, on the top surface of the tray while the other prong is pulled downwardly with the fingers which effects maximum opening of the pin for application to the hair. In order to provide clearance at the side of the tray so that the lower positioned prong can be pulled downwardly, to effect opening of the pin, I conceive to undercut, or concave, the sides of the tray from the top edge thereof to the base portion.

In order to afford a tray that will not tip as the pressure of pulling the pin open is applied on the top of the rim, I conceive to construct

the base larger in area than the projected area at the top of the rim to confine the pressure within the area of the base and thus avoid the tendency to tip under downward pressure.

5 By teaching the procedure of opening the pins by a downward pull on the lower prong while the pin rests on top of the tray rather than pushing the pin onto a wedge-shaped surface to open it, I minimize the tendency to slide the tray in the opening operation. In other words, 10 a downward pull on the top of the tray will not tend to move the tray. I further conceive to concentrate the mass of the structure at the base of the tray which will assist in retaining the tray from tipping and from moving as the pins 15 are opened thereon.

I am unaware of any tray whereon bobby pins may be opened on the outer top edge thereof by catching one of the prongs thereon and then 20 pulling the other prong down the side of the tray without being tipped or being moved about in the process. Also, I am unaware of a teaching of opening bobby pins on the top edge of a tray in this manner.

25 It is obvious that several forms of trays could be constructed that would incorporate my conceived structure of a tray that will permit bobby pins to be opened in the manner set forth on the top outer edge thereof. The accompanying drawing shows two modifications in which

Figure 1 is a plan view of my improved tray in its simplest form.

Figure 3 is a plan view of a modified form of

Figure 4 is a section taken on line 4-4, of Figure 3.

40 Referring to Figures 1 and 2, my improved tray for bobby pins comprises a relatively large base 10 having upwardly extended sides 11 to form a cavity 12 to hold the pins. The structure is generally molded of a rigid material such as

45 glass; metal; plastic, or the like, so as to afford a substantial surface on which the pins may be applied to be opened. Obviously, the structure could be of any suitable shape, such as round as shown in Figure 1, or of a scalloped design as shown in Figure 3, or it could be square or 50 rectangular or oval, or of any other desirable shape.

The upper outer corner 13 of the sides 11 of the tray is in the form of an acute angle, or wedge, effected by the top surface 14, of the sides, being inclined downwardly and the outer

surface 16, thereof, inclined inwardly and is so formed to facilitate the sliding of a bobby pin 17 slightly thereon as it is initially pushed against the said corner which would effect an initial wedging apart of the prongs and would properly position one of the prongs on the top surface 14. After the pin has been pressed properly against the corner 13 to cause the prongs of the pin to become somewhat spread apart, the final opening of the pin is accomplished by pulling the lower prong downwardly while the upper prong is left resting on the top surface 14. The initial opened pin is shown in dotted lines 17 while the final opened pin is shown in full lines 18. The pin is then held open by one's fingers until it is finally slid over the hair held by the person's other hand.

The inward inclination, or concaving, of the outer surface 16 of the sides of the tray affords clearance space for the lower prong of the pin to occupy as it is pulled downwardly from the outer top corner of the tray. Obviously proper operation of the opening of the pin would be best served if the long prong of the pin was positioned on the top surface 14. However, it has been found that the opening of the pin can be properly effected with either of the prongs being positioned on the top surface 14 while the other prong is pulled downwardly.

The base 10 is constructed substantially larger in area than the projected area at the outer top corner 13 of the sides of the tray so that the tray will not tip when the pressure required to open the pin is applied to the said corner 13. The mass of the structure, and resultant weight, is concentrated at the base of the tray and this fact combined with the fact that the construction of the tray is such that the pins are opened by a downward pull on the tray rather than a push on the same, affords a structure that will not slide about during the process of opening pins thereon.

Therefore, it is not necessary that the tray be held as the pins are opened thereon which leaves one hand free to hold the hair as the pin is lifted from the tray and opened on the outer top edge of the tray with the other hand.

In the scalloped form shown in Figures 3 and 4 the effective base portion 20 of the tray is formed by the convex portions 21 of the tray having substantially vertical sides 22 that extend from the top surface 23 to the base 20. The top surface 23 inclines downwardly in the same manner and for the same purpose as the top surface 14 of the tray in the structure shown in Figures 1 and 2. The sides 24 of the concaved portions 25 of the scalloped structure are inclined inwardly to form acute, or wedge-shaped, corner portions 26 on which the pins may be initially opened in the same manner as on the corners 13 of the former described structure. As in the former structure,

the corners 26 lie substantially within the area of the base 20 so that the tray will not tip when the pressure required to pull the pins open is applied to the top of the tray.

The corner portions 26 can be easily located by feel by the following of a finger along the scalloped edge of the tray rendering it unnecessary for one to look at the tray to find the wedge-shaped corners prior to applying the pins thereto.

A felt, or other soft pad 27 is generally cemented or otherwise attached to the bottom of the tray to afford a cushion for the tray to rest on, as is common practice in the art.

As stated above, many modified forms or styles of trays may be constructed that would meet the conceived requirements set forth herein to form a tray wherein bobby pins may be conveniently opened on the top edge thereof. Therefore, I do not wish to be confined to the exact details set forth as the same may be modified within the scope of the following claims.

I claim:

1. A tray comprising a body having a base and upwardly disposed sides to form a cavity suitable to receive bobby pins, the outer surface of the said sides being concaved intermediate the outer top edge thereof and the said base, the portion of said base that supports the structure being larger in area than the projected area at the said outer top edge of the sides, the mass of the structure being concentrated at the base, the said outer top edge of the sides being substantially wedge-shaped to facilitate being wedged between the prongs of bobby pins that may be pressed thereagainst in the process of opening the said pins as set forth.

2. A tray comprising a body having a base and upwardly disposed sides to form a cavity suitable to receive bobby pins, portions of the surface of the said sides being undercut intermediate the outer top edge thereof and the said base, the portion of said base that supports the structure being larger in area than the projected area at the outer edge of the said portions of the surface of the sides, the mass of the structure being concentrated at the base, the said outer edge of the sides being substantially wedge-shaped to facilitate being wedged between the prongs of bobby pins that may be pressed thereagainst in the process of opening the said pins as set forth.
